[57] CLAIM

The ornamental design for a patient restraint, as shown and described.

DESCRIPTION

FIG. 1 is a perspective view of a patient restraint, showing my new design;

FIG. 2 is a front elevational view of the patient restraint with the components displayed separately;

FIG. 3 is a left side elevational view thereof;

FIG. 4 is a right side elevational view with the unshown component being a mirror image of that shown in FIG. 3 thereof;

FIG. 5 is a rear elevational view thereof;

FIG. 6 is a top plan view thereof;

FIG. 7 is a bottom plan view with the unshown components being mirror images of those shown in FIG. 6 thereof; and, FIG. 8 is an environmental perspective view with all of the components attached of a patient restraint showing my new design.

The broken line showing in FIGS. 1 and 8 is for illustrative purposes only and forms no part of the claimed design.
